CLAIM

The ornamental design for a shopping cart sanitization device, as shown and described.

DESCRIPTION

FIG. 1 is a front, top, and left side perspective view of a shopping cart sanitization device, showing our new design; FIG. 2 is a front, top, and right side perspective view thereof; FIG. 3 is a front, bottom, and right side perspective view thereof;

FIG. 4 is a front, bottom, and left side perspective view thereof;

FIG. 5 is an elevational front view thereof;

FIG. 6 is an elevational rear view thereof;

FIG. 7 is an elevational left side view thereof;

FIG. 8 is an elevational right side view thereof;

FIG. 9 is a top plan view thereof; and,

FIG. 10 is a bottom plan view thereof.

The broken lines depict environmental structure and form no part of the claimed design.

1 Claim, 10 Drawing Sheets
